FILING CASE

Filed June 6, 1927

Inventor:
Marlin Hatfield Poindexter,
by Arthur E. Randall, atty.

UNITED STATES PATENT OFFICE.

MARLIN HATFIELD POINDEXTER, OF NEWTON, MASSACHUSETTS.

FILING CASE.

Application filed June 6, 1927. Serial No. 196,938.

My invention relates to filing cases for holding papers and the like in classified or orderly arrangement for convenient reference, and particularly to partitions for use in filing cases of this character.

In filing cases of the character referred to the papers or the like are stacked on edge and it is customary to provide several independent partitions of stiff paper mainly for the purpose of separating the papers into groups which are indexed on said partitions. In order to provide for convenient reference to any of the papers it is necessary to leave the latter assembled or stacked within the filing case or container in a loose condition and as a result the papers and the partitions would slip down within the case and become disarranged. My invention has for its object to obviate this objectionable feature and to otherwise improve the construction of filing cases and more especially the partitions thereof. To these ends I have provided an improved filing case having the peculiar features of construction and mode of operation set forth in the following description, the novel features thereof being particularly pointed out and defined in the claims at the close of the description. My invention further consists in providing a novel partition for filing cases more particularly described later.

In the accompanying drawing:

Figure 1 is a perspective view, partly broken away, of one of the drawers or containers of a filing cabinet, the same being constructed in accordance with my invention.

Figure 2 is a plan view of one end portion of the partition shown in Fig. 1.

Figure 3 is a cross-sectional view of a filing case constructed in accordance with my invention and embodying a different form of partition from that shown in Fig. 1.

Figure 4 is a side elevation of a portion of the partition of the filing case shown in Fig. 3.

The container 1 of the filing case illustrated in Fig. 1 is herein shown as the drawer of a filing cabinet, said drawer being constructed, as usual, with a front wall indicated by dotted lines at 2, two side walls 3, 3 and two bottom boards 4, 4, the latter being separated at the middle of the drawer to provide the bottom of the latter with a longitudinal slot 5 within which is arranged the usual retaining rod 6.

The particular novelty of the structure illustrated in Figs. 1 and 2 resides in the partition 7 with several of which the drawer 1 may be provided. This partition 7 is made from an approximately rectangular piece of sheet-metal of a width slightly less than the width of the interior of the drawer 1 and of a height greater than the sides 3, 3 of the drawer. The lower edge of this sheet-metal partition 7 is provided at its middle with a tab or tang 8 which projects down into the slot 5. This tang 8 is made at its middle with an aperture or hole 9 to receive the retaining rod 6 around which it fits loosely.

Each side marginal portion of the sheet-metal partition 7 is moulded to provide upon one side of said partition a vertical groove 10 preferably extending from top to bottom of said partition, and upon the opposite side thereof a vertical rib 11. As will be clear this moulding of the marginal portion of the sheet metal partition 7 very effectually stiffens the latter thus permitting the use of quite thin sheet-metal from which to produce the partition. The main purpose, however, of thus moulding each side marginal portion of the sheet metal partition is to provide the latter with means to interlock with a vertically adjustable spring clip rest 12.

Each spring clip 12 is made with a pair of oppositely disposed spring arms 13 and 14 to embrace and grip the side marginal portion of the partition, the former being made with a transverse rib 15 to occupy the groove 10 and the latter being made with a transverse socket or groove 16 to be occupied by the rib 11. As will be clear the grip of the two arms 13 and 14 upon the partition 7 serves to frictionally hold the clip in adjusted position while the engagement of the rib 15 and socket 16 with the groove 10 and rib 11, respectively, not only interlocks the clip with the partition so that the former will not readily be displaced endwise but this engagement also serves to hold the clip at right angles to the side edge of the partition.

Between the two arms 13 and 14 of clip 12 and at the outer ends thereof is provided a transverse abutment bar 17 which by engagement with the side edge of the partition positively holds the outer end of the clip a certain desired distance away from the side edge of the partition 7.

Each partition of the file may be con-

structed as described and will include two clips 12, one at each side thereof. These two clips are adjusted vertically to occupy positions where, by engagement with the top edges of the sides 3, they support the partition with its lower edge just out of contact with the bottom boards or panels 4 of the drawer, and it will be clear that since the outer ends of the clips 12 are extended beyond the planes of the front and back side faces of the partition they will support the latter in a vertical position.

The top edge of the partition 7 may be provided with an upwardly extending tab 15 or tang 18 to receive, as usual, suitable indicia. In practice, I finish the partition by lithographing the side surfaces thereof with the indicia, or any other desired printed matter, upon the same with the result that 20 the partition is both ornamental and serviceable and will not be injured or defaced by handling as has heretofore been the case with partitions made from wood, cardboard or the like.

In Figs. 3 and 4 I have illustrated another form of partition 19 wherein the side rests are constituted by integral side lugs 20, 20 each of which has its lower edge curled or bent to form an approximately cylindrical 30 lower portion 21, Fig. 4, the distinguishing feature of which is that it does not present a knife edge to engage the tops of the sides 3, 3 of the drawer and thereby interfere with free movement of the partition thereon, but 35 affords an edgeless bearing surface for engagement with the top of the sides 3 so as to provide for free movement of the partition thereon. While the clips 12, 12 are made of 40 spring sheet-metal and rest edgewise upon the tops of the sides of the drawer, nevertheless the outer ends of these clips being extended laterally well beyond the planes of the front and back surfaces of the partition, said clips each cover or engage an extended 45 surface as to provide for free sliding movement of the clip on the top of the side of the drawer.

The form of partition shown in Figs. 3 and 4 of the drawing can be used only with

a drawer having sides of a particular height 50 but the form of partition shown in Figs. 1 and 2 provides for vertical adjustment of the clips 12 to adapt the partition to the height of the sides 3 whatever the same may be. Therefore, this form of partition shown in 55 Fig. 1 is adapted to be produced separately as a new article of manufacture and sold for incorporation in filing cabinets or cases that are already in use.

What I claim is:

1. A partition for filing cases including a body consisting of a single piece of sheet-metal provided at each side edge thereof with a shoulder for directly engaging one side wall of a container, said shoulder being made from sheet metal bent laterally so that it is of greater width than the thickness of said body.

2. A partition for filing cases including a body of sheet-metal having opposite parallel side edges and shoulder-providing clips engaged with said opposite edges and adjustable vertically on said partition.

3. A partition for filing cases including a body of sheet metal having its opposite side marginal portions each moulded to provide a vertical groove upon one face of the partition and a vertical rib upon the opposite side thereof, and a pair of spring shoulder-providing partition-supporting clips embracing and interlocking with said moulded side marginal portions with provision for vertical adjustment.

4. A partition for filing cases comprising a body of sheet metal having opposite parallel side edges and having its opposite side marginal portions each moulded to provide a vertical groove upon one face of the partition and a vertical rib upon the opposite side thereof, and a pair of shoulder-providing partition-supporting clips each made with a pair of spring arms embracing one of said moulded side marginal portions and interlocking with said groove and rib thereof.

Signed by me at Boston, county of Suffolk 95 and State of Massachusetts, this 26th day of May, 1927.

MARLIN HATFIELD POINDEXTER.
